Primary Examiner — Catherine Ho(74) *Attorney, Agent, or Firm* — Latimer LeVay Fyock
LLC(57) **CLAIM**

I claim the ornamental design of the sign, as shown and described.

DESCRIPTION

FIG. 1 is a front exploded perspective view of a sign shown in an environment of use, showing my new design;
 FIG. 2 is a bottom perspective view of a sign;
 FIG. 3 is a front elevational view of FIG. 1;
 FIG. 4 is a rear elevational view of FIG. 1;
 FIG. 5 is a left side elevational view of FIG. 1;
 FIG. 6 is a right side elevational of FIG. 1;
 FIG. 7 is a top plan view of the sign;
 FIG. 8 is a bottom plan view of the sign; and,
 FIG. 9 is an enlarged detailed view of encircled area 9 in FIG. 2.

The broken lines in the drawings show environment that form no part of the claimed design.
